United States Patent Office

Des. 216,596
Patented Feb. 17, 1970

216,596

TROPHY

Dorothy K. Allen, Libertyville, Ill., assignor to F. H. Noble & Company, Chicago, Ill., a corporation of Illinois

Filed Dec. 13, 1967, Ser. No. 9,761

Term of patent 14 years

Int. Cl. D11—02

U.S. Cl. D29—28

FIG. 1 is a front elevational view of a trophy showing my new design;

FIG. 2 is a side elevational view of the trophy shown in FIG. 1;

FIG. 3 is a top plan view of the trophy shown in FIG. 1;

FIG. 4 is a perspective view of the trophy shown in FIG. 1 with the bowl cover removed;

FIG. 5 is a front elevational view of the trophy shown in FIG. 4;

FIGS. 6, 7, 8, 9 and 10 are a series of sectional views taken along the lines 6—6, 7—7, 8—8, 9—9, and 10—10, respectively, of FIG. 5;

FIG. 11 is a side elevational view of the trophy as shown in FIG. 5;

FIG. 12 is an end view taken along the line 12—12 of FIG. 11;

FIGS. 13 and 14 are sectional views taken along the lines 13—13 and 14—14, respectively, of FIG. 11;

FIG. 15 is a top plan view of the trophy as shown in FIG. 5; and

FIG. 16 is a bottom plan view of the trophy as shown in FIG. 5.

The dominant features of my design are shown in full lines.

I claim:

The ornamental design for a trophy, substantially as shown and described.
